CLAIM

The ornamental design for a shop floor data terminal or the like, as shown and described.

DESCRIPTION

FIG. 1 is a top, front, right side perspective view of the shop floor data terminal or the like showing my new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and

FIG. 7 is a rear elevational view thereof.

The digits shown in broken lines in FIGS. 1, 2, and 6 are used for illustrative purposes only and form no part of the claimed design.

FIG. 1
